United States Patent Office

Des. 201,495
Patented June 29, 1965

201,495

BRICK COLUMN

Donald J. Dirkse, Midland, Mich., assignor to The Dow
Chemical Company, Midland, Mich., a corporation of
Delaware

Filed Apr. 10, 1963, Ser. No. 74,386

Term of patent 14 years

(Cl. D13—4)

Fig. 2

Fig. 1

FIGURE 1 is an elevational view of a brick column showing my new design; and

FIGURE 2 is a top plan view thereof.

I claim:

The ornamental design for a brick column, substantially as shown.
